UNITED STATES PATENT OFFICE.

ROBERT WALKER SMITH, OF ASTWOOD BANK, ENGLAND.

STEERING-LOCK FOR SAFETY-BICYCLES.

SPECIFICATION forming part of Letters Patent No. 588,665, dated August 24, 1897.

Application filed November 24, 1896. Serial No. 613,342. (No model.)

To all whom it may concern:

Be it known that I, ROBERT WALKER SMITH, a subject of Her Majesty the Queen of Great Britain and Ireland, residing at Astwood Bank, in the county of Worcester, England, have invented certain new and useful Improvements in and Connected with Steering-Locks for Safety-Bicycles and other Front-Steering Velocipedes, of which the following is a specification.

This invention has reference to what are known as "friction steering-locks," which are used on safety-bicycles and other front-steering velocipedes to lock the steering-pillar in the steering-head of the machine with the steering-wheel in a line or at any desired angle to the back wheel, so that when thus locked the safety-bicycle can readily be supported leaning against a wall or other support.

My invention consists of an improved construction of the said friction band or lock and method of applying the same whereby it can very readily be applied to any make of front-steering cycle without the necessity of a special top lug or bottom lug for the cycle-head and there is no tendency to strain the steering-pillar from its true central position in the steering-head of the machine, which is a serious defect in most of the band steering-locks heretofore employed.

I will describe my invention by referring to the accompanying drawings, on which—

Figure 1 is a side elevation of the steering-pillar and front fork of a safety-bicycle or other front-steering velocipede with my improved steering-lock applied to the upper part of the same. Fig. 2 is a side elevation of the same, on an enlarged scale, without the front fork. Fig. 3 is a sectional plan through line X X of Fig. 2. Fig. 4 is a side elevation of the upper part of the steering-head shown in Figs. 1 and 2, but with the steering-lock removed. Fig. 5 is a plan, and Fig. 6 is a front elevation and part section, of the steering-head and steering-pillar with my improved steering-lock applied to the lower part of the same; and Fig. 8 shows the lower part of the steering-head and the upper part of the front-fork crown of Fig. 7 with the steering-lock removed.

The same letters of reference indicate the

same or corresponding parts in all the figures of the drawings.

In one arrangement of my invention, as illustrated by Figs. 1, 2, 3, 4, 5, and 6, I arrange for the band-clip A to encircle the steering-pillar B where the top lug C of the cycle-head meets the upper collar D of the ball-head which is fixed on the steering-pillar B, and the edges c' d' of those parts are turned so as to form a V or other groove (see Fig. 4) for the friction-band A to lie in, so that the said friction-band when tightened up grips both the upper edge c' of the top lug C and the lower edge d' of the ball-head collar D, and thus prevents the steering-pillar (to which the ball-head collar D is fixed) from turning round. The steering-band A (shown separately by Figs. 5 and 6) is by preference made of a half-round section, the rounded side fitting in the groove between the edges d' c'. One end of the friction-band clip A has formed with it or fixed to it an eye E, through which the screw-threaded end a' of the band-clip A passes, this end a' having the milled nut F screwed on it for tightening up the band. The front boss part f' of the nut F is by preference reduced so as to fit in the eye E. In order to prevent the band A from turning with the steering-pillar, the eye part E of the band fits and engages in the recess C², which I form in the top lug C of the steering-head.

When the clip friction-band A is tightened up, as above described, it tightens equally on the top lug C (which, as aforesaid, forms a part of the cycle-frame) and on the ball-head collar D, which turns with the steering-tube B and has no tendency to strain the steering-tube B out of its central position in the ball-head C, as the tightening up of the collar A imparts a slight upward movement to the steering-tube B in the direction of its axis, tightening the fork-crown G (which is fixed to the bottom of the steering-tube B) against the ball-bearing in the bottom lug H of the machine-frame.

Instead of my improved friction-band clip A being applied to the top lug C of the machine-head, as above described, and illustrated by Figs. 1, 2, 3, and 4, I may, as shown by Figs. 7 and 8, similarly apply my improved

friction clip-band to act upon the lower edge h' of the bottom lug H and on the upper edge g' of the fork-head collar or crown G, the edges $h' g'$ of the parts H and G, which are 5 clipped by the friction-band A, being by preference chamfered or coned, as shown in Fig. 8, for the friction-band A to grip and bear against. The bottom lug H has also a recess h^2 formed in it, in which the eye part E of the 10 friction clip-band A engages and fits to prevent the friction-band A from turning with the steering-tube B.

What I claim as my invention, and desire to secure by Letters Patent, is—

- 15 1. In combination, the fixed head of a bicycle, the steering-pillar passing through the same to turn therein, and to have a slight longitudinal movement, said pillar having an upper and a lower boss or collar adjacent to the 20 ends of the fixed head, the parts at one end of the fixed head having a groove between them and a wedging clamp band or ring fitted to said groove, to bear on the adjacent edges of the parts, with means for tightening the 25 same and moving the pillar longitudinally to make its boss or collar bear on the opposite end of the fixed head, substantially as described.
- 30 2. The combination with the steering-pillar and fixed steering-head of a safety-bicycle or other front-steering velocipede, which pillar is adapted to have slight longitudinal movement in the steering-head, of a separate gripping-band which encircles and fits in a groove 35 formed between the lower edge of the upper collar of the steering-pillar and the upper edge of the fixed steering-head, the said gripping-

band having a wedging contact and an eye at one end through which the other screw-threaded end of the band passes this screw-threaded 40 end having a nut by turning which the band can be caused to grip the collar of the steering-pillar and the steering-head thereby imparting a longitudinal thrust on the steering-pillar and locking the same in the steering-head substantially as hereinbefore described. 45

3. In combination, the fixed steering-head, the steering-pillar passing through the same to have a rotary and slight longitudinal movement therein, the bosses or collars on the pillar adjacent to the ends of the steering-head, a clamping-band passing around the joint between the end of the fixed head and the boss on the steering-pillar, the eye part of said band and the recess in one edge of the joint 55 receiving the same to hold the band against circumferential displacement, substantially as described.

4. In combination, the fixed steering-head, having one end beveled, the steering-pillar 60 having a collar with a beveled edge adjacent to the beveled edge of the fixed head and a clamping-band of substantially wedge shape in cross-section with means for tightening it, said band bearing on the beveled edges to give 65 the steering-pillar a longitudinal thrust, substantially as described.

In witness whereof I have hereunto set my hand in presence of two witnesses.

ROBERT WALKER SMITH.
